United States Patent Office

Des. 196,914
Patented Nov. 19, 1963

196,914

ELECTRONIC CONTROL BOX

John Ray Regal, Elizabeth, N.J., assignor to Sperry Rand Corporation, New York, N.Y., a corporation of New York

Filed Oct. 15, 1962, Ser. No. 72,107

Term of patent 14 years

(Cl. D26—5)

FIG.1

FIG.2

FIG. 1 is a front perspective view of an electronic control box embodying my new design; and

FIG. 2 is a rear perspective view thereof.

The dominant features of my new design are shown in solid lines in the drawing.

I claim:

The ornamental design for an electronic control box, substantially as shown and described.
